ROTARY STEPPER SWITCH

Walter M. Ostrander, New Milford, and Sinclair N. Sutherland, New Haven, Conn., assignors to Consolidated Electronics Industries Corp., Waterbury, Conn., a corporation of Delaware

Filed Feb. 17, 1966, Ser. No. 528,300
10 Claims. (Cl. 335—122)

The present invention relates to rotary electrical switches, and more particularly to improvements in miniaturized, torsion spring driven, solenoid operated, stepper switches of the type adapted to be used in sonar buoys and other like devices where unusually high deceleration forces and shock are encountered in their intended applications.

Specifically, the miniaturized switch of the present invention represents certain improvements over the stepper switch disclosed and claimed in the copending application of Walter M. Ostrander, Arthur W. Bennett, and Sinclair N. Sutherland for "Rotary Stepper Switch," Ser. No. 306,185, filed Sept. 3, 1963, and now U.S. Patent No. 3,236,970.

The new switch, while performing the functions of the patented switch, is of a more simplified and improved construction, which lends itself to faster and more economical production and provides more reliable and improved performance. More specifically, the rotary stepper switch of the present invention includes a rotor which is rotated periodically by a clock spring under the control of an escapement mechanism to effect, in cooperation with a plurality of contacts, a predetermined switching sequence. The escapement is of the novel type disclosed in the Patent No. 3,236,970, and it unlocks the rotor for rotation when the rotor shaft is alternately axially displaced by a solenoid or spring force.

In accordance with the present invention, the rotor of the stepper switch includes a predetermined array of shorting elements, advantageously in planar or so-called "printed circuit" form. Moreover and as an important aspect of the invention, the rotor is biased in an axial direction by spring-loaded contact elements in order that they may be constantly wiped by the rotor as it is rotated. Furthermore, the bias provided by the springs associated with the contact elements serves to unlock the escapement when the solenoid is de-energized. As a still further aspect of the invention, the springs which provide the requisite biasing forces for each of the contact elements also serve as conductors to connect the contact elements directly to the circuitry in which the sequential switching operations are being performed. It will be understood that the disposition of the contact elements and the configuration of the shorting elements may be appropriately arranged to provide any desired switching sequence.

As will be appreciated, the new and improved arrangement enables rotary stepper switches of the type described to be assembled more easily and with less exacting tolerances than have been heretofore necessary. Moreover, other simplifications to be described in detail hereinafter have been incorporated in the switch construction to reduce costs, to simplify the manufacture of parts and their subsequent assembly into a finished product, and to improve the reliability and accuracy of the sequential switching provided by the stepper switch.

For a more complete understanding of the present invention and its attendant advantages, reference should be made to the following detailed description of its construction and operation taken in conjunction with the accompanying drawings, in which:

FIG. 1 is an enlarged bottom plan view of the rotary

2

stepper switch of the present invention along with its associated printed circuitry;

FIG. 2 is a further enlarged, cross-sectional view of the switch of the invention taken along line 2—2 of FIG 1;

FIG. 3 is a cross-sectional view of the switch taken along line 3—3 of FIG. 2 and showing details of construction of the rotor and escapement; and

FIG. 4 is a fragmentary perspective view of the locking ring of the escapement.

Referring first to FIG. 2, the new and improved switch 10 includes a substantially cylindrical housing 11 which is open at both ends and may be advantageously fabricated in the form of an aluminum casting. The bottom or lower end of the housing 11 is closed by a cap 12, while the top or upper end of the housing is closed by a dielectric board 13 which supports a plurality of "printed" conductors 14 thereupon, which conductors comprise part of an external pulsing circuit for a solenoid coil 15.

Advantageously, pulsing circuitry for the solenoid 15, including circuit elements 16 (such as capacitors, resistors, silicon controlled rectifiers, etc.), may be arranged on and between the board 13 and a similar board 17 which is spaced downwardly from the top of the housing, as shown in FIGS. 2 and 3. Both of the circuit boards 13, 17 may be made from a glass epoxy material and interconnecting posts 18 may be disposed therebetween, which posts may extend from the boards as terminal posts. Also supported on the circuit board 13 are a plurality of "printed" output conductors 19.

More specifically and in accordance with the invention, a plurality of spring-biased, switch contacts 21, 22, 23, 24, 25, 26 are supported in a circular block 27. Each of the contacts has enlarged annular head portions 21a—26a which are disposed for axial movement in cylindrical openings 29 formed at the upper face of the block 27. As shown in FIG. 2, the contacts have pointed shank portions 21b—26b which project downwardly and through openings 30 formed at the lower face of the block 27. In accordance with the invention, biasing springs 31, having their upper free ends connected by solder 32 to the conductors 19, are disposed in each of the openings 29 with their lower ends in downwardly biasing contact with the heads 21a—26a of the contacts 21—26. As shown, the block 27 is fastened to printed circuit board 13 by one or more screws 32.

In accordance with the inventive principles, the contacts 21—26 are selectively electrically connected by outer and inner printed shorting rings 36, 37, respectively, which are generally concentrically arrayed on a dielectric rotor disk 38 made of an epoxy glass material. The disk 38 is supported through a bushing 40 for rotation and axial displacement by shaft 39, which itself is supported for rotation and axial displacement by an inner housing member 41. The rings 36, 37 are electrically independent of one another but include radially inwardly projecting tab portions 36a, 37a, respectively.

More specifically, contact element 26 is disposed radially most outwardly of the axis of rotation of the rotor shaft 39 while contact element 21 is disposed radially most inwardly of the axis. The remaining contacts 22—25 are disposed at a radius intermediate those of the contacts 21, 26 and along an arc which lies between (in a counter-clockwise direction) the contacts 26, 21.

Thus as the rotor 39 is stepped (counterclockwise, for example) the outer shorting ring 36 will periodically and sequentially connect, through its tab portions 36a, the outermost contact element 26 with each of the contact elements 22—25. Likewise, the inner shorting ring 37 will periodically and sequentially connect, through its tab portion

37a, the innermost contact element 21 with each of the contact elements 22-25.

As will be appreciated, by selectively arranging the angular displacements between individual ones of the contact elements, the angular displacements between the tab portions of the shorting rings, and the radial locations of the contact elements, a variety of switching sequences may be established. Thus, as the spring-biased contacts 21-26 are wiped by the steppingly rotated printed rotor disk, a selected switching sequence between the contacts is performed, which switching sequence may be externally derived at the printed conductors 19 by virtue of the interconnecting conductive springs 31.

Stepping of the rotor shaft 39 and the rotor disk 38 attached thereto through a hub 40 is effected under the control of an escapement mechanism of the type claimed in the above-identified application and through torsional motive power provided by a wound clock spring 60 which is appropriately, fixedly connected between the cap 12 and the lower end 61 of the shaft 39. The escapement includes an escape tooth 45 which is affixed to the rotor shaft 39 through the hub 40 and which is locked against radial advance in an upper plane by upper teeth 46 and in a lower plane by lower teeth 47. The teeth 46, 47 are in the form of a lock ring 55 which is supported in the inner housing 41 by a pin 56, as shown in FIG. 3.

As the escape tooth 45 is axially displaced from one plane to the other, it is freed for limited rotation until it engages the next successive locking tooth in its path. Thus, the rate of rotation or stepping of the rotor shaft 39 is determined by the rate at which the escape tooth 45 is unlocked by an axial displacement into one or the other planes of the locking teeth 46, 47. To that end, a solenoid coil assembly 49 including the coil 15 is mounted in the inner housing 41. When periodically energized through the above-described pulsing circuit to which it is connected by leads 50, the solenoid coil attracts an armature plate 52, which is loosely mounted adjacent a shoulder 53 formed in the shaft 39. As will be understood, the attraction of the armature plate 52 by the coil causes it to displace the shaft 39 axially upward. In turn, this moves the locking tooth 45 out of the lower plane of the teeth 47 and into the upper plane of the teeth 46, thereby permitting an incremental rotational advance of the shaft 39 under the influence of the clock spring 60. Upon de-energization of the solenoid coil, the escape tooth 45 is returned by the spring-biased contacts 21-26 to the lower plane for a further incremental advance.

As described in more detail in the copending application, the inner housing may be keyed through a key 61 to the housing 11 by a keyway 62 formed therein for limited axial displacement when subjected to deceleration forces F, such as may be experienced in sonar buoy applications when the switch 10 is dropped into the sea from great altitudes. A shock spring 65 acting between the top of the switch assembly (defined by the printed circuit board 13) and an annular shoulder 66 formed in the inner housing resists displacement of the inner housing against the deceleration forces. A limit upon the upward displacement of the rotor shaft 39 is provided by a stop 67 staked or otherwise secured to the printed circuit board 13, as shown in FIG. 2.

Advantageously and as shown best in FIGS. 1 and 2, the cap 12 is secured to the outer housing 11 by a spring clip 70 which has diametrically inwardly opposed locking prongs 71 which project through openings 72, 73 formed in the outer housing and cap, respectively. As will be understood, the prongs of the clips may be spread apart while the clip is in a plane normal to that of the cap. After the cap is locked to the housing, the clip may be pivoted into the plane of the cap as indicated in FIG. 2. A protective plastic sleeve 74 covers the central, generally U-shaped portions of the clip.

The operation of the stepper switch is relatively simple. Torsional motive power for the rotor shaft 39 is provided

by first rotating the cap 12 to wind the clock spring 60. When the spring is wound, the cap is clipped to the housing by the spring clip 74, as shown in FIG. 1.

The escape tooth 45 and the rotor disk 38 will assume a position in the plane of the lower locking teeth 47 under the influence of the spring biased contacts 21-26. As will be understood, in the absence of axial displacement the shaft 39 is restrained against rotation by the cooperation of the escape tooth 45 with the locking teeth. Thereafter, the application of an energizing pulse to the solenoid coil 15 will cause the shaft 39 to be axially upwardly displaced, thereby freeing the escape tooth 45 from the lower teeth 47. Upon being freed, the escape tooth and the shaft 39 are rotated under the influence of the stored energy in the clock spring until the escape tooth is blocked by an upper tooth 46. Upon de-energization of the coil, the escape tooth will be displaced axially downwardly by the spring loaded contacts, thereby being freed to allow a further incremental advance of the shaft under the influence of the clock spring 60 until the escape tooth is halted by a lower tooth 47.

As will be appreciated, the periodic pulsing of the solenoid coil will cause the rotor disk 38 to be rotatably stepped in synchronism with the pulsing rate. It will be understood that, the circuit conditions or switching sequence at each step are determined by the specific interrelationship of the inner, outer and intermediate contacts with the printed shorting rings, which interrelationship may be changed as desired or found necessary to meet a variety of stepping switching applications.

The above-described rotary stepping switch provides extremely reliable and efficient operation. Furthermore, the new and improved arrangement of parts results in substantial cost savings in the manufacture of stepping switches of this general type.

It should be understood that the specific switch mechanism herein illustrated and described is intended to be representative only, as certain changes may be made therein without departing from the clear teachings of the disclosure. Accordingly, reference should be made to the following appended claims in determining the full scope of the invention.

We claim:

1. In a miniaturized rotary stepper switch of the type including a rotor shaft mounted in a housing for step-by-step rotation under the influence of a rotary drive means and a reversibly axially displaceable escapement means, the improvement comprising

- (a) a substantially planar, disklike rotor element carried by said shaft;
- (b) planar shorting means carried by said rotor shaft;
- (c) a plurality of switch contacts disposed adjacent to said shorting means;
- (d) means supporting said contacts for limited axial displacement in said housing;
- (e) biasing spring means urging said contacts in a predetermined axial direction;
- (f) said contacts engaging said rotor element and thereby urging said rotor in said predetermined axial direction;
- (g) electromagnetic means selectively energizable to displace axially said rotor in a direction opposite to said predetermined direction and against the force of said biasing springs;

(h) whereby the periodic energization of said electromagnetic means causes alternate axial displacements of said rotor shaft of sufficient magnitude to unlock the escapement means and thereby causes a subsequent step-by-step advance of said shaft under the control of said escapement means to rotate said shorting means relative to said array of switch contacts and to effect a predetermined sequential interconnection thereof.

2. A stepper switch in accordance with claim 1, in

- (a) said disklike rotor and shorting means are of printed circuit construction.
3. A stepper switch in accordance with claim 2, in which
- (a) said contacts include substantially pointed ends adapted to engage said rotor in predetermined limited areas. 5

4. A stepper switch in accordance with claim 1, in which
- (a) said shorting means include a generally circular portion and an integral tab portion extending radially therefrom; 10
- (b) said contacts are arrayed at two radial distances from the axis of rotation of said rotor, one radius terminating within said generally circular portion of said shorting means and the other radius terminating within said tab portion. 15

5. A stepper switch in accordance with claim 1, in which
- (a) said rotary drive means comprises a torsion spring; 20
- (b) a selectively rotatable cap is included in said housing;
- (c) said torsion spring is connected between said housing and said cap;
- (d) a removable spring clip means fastens said cap to said housing. 25

6. A stepper switch in accordance with claim 1, in which
- (a) said means supporting said contacts is a dielectric block;
- (b) said block is mounted on a printed circuit board which closes off an end of the housing; and
- (c) said printed circuit board includes output circuitry. 30

7. A stepper switch in accordance with claim 6, in which
- (a) said block defines a plurality of cylindrical openings in which said contacts are disposed for limited axial displacement;
- (b) said biasing spring means comprise individual coil springs disposed in each of said openings; 40
- (c) said coil springs connect said contacts to said output circuitry.

8. A stepper switch in accordance with claim 3, in which

- (a) said shorting means include first and second generally circular portions which are generally concentric and are electrically independent;
- (b) said first and second circular portions having first and second integral radially extending tab portions, respectively;
- (c) said contacts are arrayed at three radial distances from the axis of rotation of said rotor;
- (d) a first radius terminating within said first circular portion, a second radius terminating within said second circular portion, a third radius terminating within one of said tab portions;
- (e) at least one of said first and second tab portions intersecting one of said second and first circular portions, said intersecting portions being electrically independent and being separated by an area greater than the area of said pointed ends of said contacts. 9.

In a rotary stepper switch of the type including a rotor shaft mounted in a housing for step-by-step rotation under the influence of a rotary drive means and a reversibly axially displaceable escapement means, the improvement comprising

- (a) a rotary contact element carried by said rotor shaft;
- (b) a plurality of spring biased contact elements acting on said rotary contact element and being collectively operative to urge said rotary element and said shaft in a first axial direction; and
- (c) selectively energizable means for moving said rotary contact element and said shaft axially in opposition to the collective action of said spring biased contact elements.

10. A rotary stepper switch according to claim 9, further characterized by

- (a) all of said spring biased contact elements act in the same direction as said rotary contact element.
